CLAIM

The ornamental design for a scent-dispersing toilet bolt finial, as shown and described.

DESCRIPTION

FIG. 1 is a perspective view of a scent-dispersing toilet bolt finial showing my new design with environmental structure shown in evenly-spaced dash broken line;

FIG. 2 is an enlarged-scale perspective view of detail II-II in FIG. 1 with environmental structure shown in evenly-spaced dash broken line;

FIG. 3 is an obverse elevational view thereof, the reverse side being a mirror opposite view;

FIG. 4 is a side elevational view thereof, the opposite side being a mirror opposite view;

FIG. 5 is a top plan view thereof; and,

FIG. 6 is a bottom plan view thereof wherein the dot-dash broken lines encircle or represent portions of the scent-dispersing toilet bolt finial that form no part of the claimed design.

The evenly-spaced dash broken lines in the drawing represent environmental subject matter that forms no part of the claimed design. The dot-dash broken lines in the drawings encircle or represent portions of the scent-dispersing toilet bowl finial that form no part of the claimed design.
